UNITED STATES PATENT OFFICE.

ALEXANDER I. KRYNITZKY, OF PHILADELPHIA, PENNSYLVANIA.

AUTOMATIC GAS CUT-OFF OR ALARM.

1,294,484.

Specification of Letters Patent.

Patented Feb. 18, 1919.

Application filed April 24, 1918. Serial No. 230,580.

To all whom it may concern:

Be it known that I, ALEXANDER I. KRYNITZKY, a citizen of Russia, residing at Philadelphia, in the county of Philadelphia and State of Pennsylvania, have invented new and useful Improvements in Automatic Gas Cut-Offs or Alarms, of which the following is a specification.

This invention relates to new and useful improvements in apparatus for automatically stopping the flow of gas when the flame should become extinguished or for sounding an alarm or both.

Another object of the invention is to employ a body which will expand under the action of heat and to utilize the movement of this body for operating means for controlling the gas or sounding the alarm. This body may be of any desired material, either solid, liquid or gaseous which will be expanded or contracted by the action of heat or the lack of heat.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a sectional view of one form of the invention.

Fig. 2 is a side view.

Fig. 3 is a detail view of one of the electric contacts.

Fig. 4 is a sectional view of a modification.

Fig. 5 is a sectional view of another modification.

Figs. 6 and 7 are views of other modifications. 50

Fig. 8 is a front view of still another modification.

Fig. 9 is a longitudinal section through Fig. 8. 55

Fig. 10 shows a slightly different arrangement of the contact finger from that shown in Figs. 1 and 2.

Fig. 11 is another modification.

Referring more particularly to these drawings and to the form of the invention shown in Figs. 1, 2 and 3, the reference character 1 indicates a semi-circular supporting member and shield having an upwardly extending tubular extension 2, which supports a sector shaped dial 3 at its upper end. A collar 4 on said extension 2 engages the lower end of a brace 5 for said dial. The members 1 and 2 may be made of asbestos or any other suitable material and 70 said members are supported in any desired manner adjacent to the gas burner so that the heat from the flame will be directed on to the partially spherical member 6 supported in the member 1. This member 6 has its upper end closed by a membrane 6' and is adapted to contain air or gas which will be expanded when subjected to heat.

I prefer to make the member 6 of copper and the membrane of a thin sheet of copper, 80 though it will be understood that any other suitable material may be used to form said part. 7 is a rod passing upwardly through the tubular member 2 and having its lower end connected with the membrane 6'. The upper end of the rod is connected with the small end of a sector shaped lever 8, pivoted intermediate its ends to the rear face of the dial, as at 9. The enlarged end of said lever has its edge provided with teeth, which 85 engage a toothed wheel 10 carried by a shaft 11 journaled in the dial. The said shaft is connected with a contact finger 12, which is made of conducting material. The shaft 11 is also made of conducting material and 90 is suitably insulated from the dial and this shaft has connected thereto one of the terminal wires 13 of an electric circuit. The

95

other terminal wire 14 of this circuit is connected with a spring contact 15 carried by the dial and suitably insulated therefrom. This contact is normally held in inclined 5 position as shown in Fig. 3 so as to set up a wedge action with the finger to insure a proper contact between the parts. 16 indicates a latch pivoted to the dial and adapted to engage the end of the finger to hold 10 the same in raised position and out of engagement with the spring contact. 17 indicates a plurality of rollers carried by the member 2 and engaging with the rod 7. I may make the dial of non-conducting material so as to render unnecessary the insulation of the contact and shaft therefrom. I may also cover the inside of the member 1 15 with thin metal which acts as a reflector.

The electric circuit may be connected with 20 means for controlling the flow of gas through the burner or with means for sounding an alarm, or both, when the circuit is closed.

While the gas is unlighted the finger is 25 held in raised position by means of the latch 16. After the gas is lighted the heat from the flame will cause the expansion of the air or gas within the member 6 so that the membrane 6' is raised, and thus the rod 7 will be 30 moved upwardly to oscillate the lever 8. This will cause the finger to remain in raised position. The latch 16 is then swung outwardly away from the finger. The device is now set so as to operate the before mentioned mechanism if the flame should become extinguished. If this should happen 35 the air or gas in the member 6 will contract and thus permit the membrane to lower. This will cause the rod to drop and rock 40 lever 8, and said lever through the wheel 10 and shaft 11 will swing the finger 12 downwardly into engagement with the contact 15 so as to complete the electric circuit and thus sound the alarm or shut off the gas.

45 In the modification shown in Fig. 4 the rod 7' is located in a tube 18, preferably made of iron and having a spherical lower end 19. This spherical lower end contains mercury and the end of the rod is provided 50 with a piston 20 which rests on said mercury. In this way the expansion and contraction of the mercury will cause the movement of said rod, which will operate the parts as before described.

55 In the modification shown in Fig. 5 I locate a cylinder 21 of graphite between the mercury and piston. In other respects this form is similar to that just described.

In the modification shown in Fig. 6, in 60 stead of making the lower end of tube 18 spherical I make it semi-spherical as indicated at 22 in said figure. In other respects this form is similar to that shown in Fig. 4.

In the modification shown in Fig. 7 the

rod 7" is made of expandible metal and has 65 its lower end seated in a tubular member 23. This member is made of quartz, or similar material and supports the rod adjacent the flame of the burner. In other respects this modification is similar to that shown in the 70 other figures.

In the modification shown in Figs. 8 and 9, 24 indicates a frame having a recess 25 in its front face in which is seated a spherical member 26. The upper end of this member 75 has connected therewith a hollow spiral tube 27, the other end of which is bent at right angles and passes through a curved slot 28 formed in the frame. A finger 29 pivoted at 30 to the frame has its extreme end connected with said end of the tube. The rear face of the frame 24 is provided with a shelf 31 on which is seated a battery 32. The wires from this battery pass to the spring contact 33 carried at the top of the frame and with 35 which the finger is adapted to engage. The other wire of the circuit is connected with the pivot 30. The alarm or shut off means for the gas is connected with said circuit and the spherical member and tube contain air 90 or gas so that the expansion and contraction of same will cause the end of the tube to move in the slot and thus oscillate the finger to make and break the electric circuit, as before described. 95

In the modification shown in Fig. 10 the finger 29' is pivoted to the dial, as at 29" and its end is connected directly with the rod 7" so as to render the use of the lever 8, in Figs. 1 and 2, unnecessary. 100

In the modification shown in Fig. 11 the form of the frame 24" is slightly different from that before described, but in the other respects this form is similar to that shown in Figs. 8 and 9. 105

I prefer to omit the latch 16 and to place an ordinary switch in the circuit. In this case when the gas is not lighted the pointer or finger 12 will rest against the contact 15. When the gas is lighted the finger will rise 110 off the contact 15 and then the switch may be closed, so that if the gas should become extinguished the finger will drop and complete the circuit.

When desired the finger may be attached 115 to mechanical means for operating the alarm or controlling the gas, so as to use the device with means other than electrical means.

It is thought from the foregoing description that the advantages and novel features 120 of my invention will be readily apparent.

I desire it to be understood that I may make such changes in the construction and in the combination and arrangement of the several parts, provided that such changes 125 fall within the scope of the appended claim.

What I claim is:—

A device of the class described comprising

- a combined supporting member and shield adapted to be located adjacent a burner, said member having a semi-circular recess in its lower part and an upwardly extending part, 5 an expansible body having a substantially spherical part located in said recess, a contact finger carried by the upper part of said member for actuating devices for sounding an alarm or for shutting off the gas, and means for connecting the finger with the ex- 10 possible body.

In testimony whereof I affix my signature.

ALEXANDER I. KRYNITZKY.
